(57) **CLAIM**

The ornamental design for a memory card reader for programmable controller, as shown and described.

DESCRIPTION

FIG. 1. is a perspective view of the front, top, and left sides of a memory card reader for programmable controller showing our new design;

FIG. 2. is a perspective view of the rear, bottom, and right sides thereof;

FIG. 3. is a front view thereof;

FIG. 4. is a rear view thereof;

FIG. 5. is a top plan view thereof;

FIG. 6. is a bottom view thereof;

FIG. 7. is a right side view thereof; and,

FIG. 8. is a left side view thereof.

The broken lines shown represent portions of the memory card reader for programmable controller and form no part of the claimed design.
